Application filed September 17, 1932. Serial No. 44,881. Term of patent 3½ years.

To all whom it may concern:

Be it known that I, WILLIAM WILLHEIM, a citizen of the United States of America, residing at 115 Central Park West, in the city of New York, county of New York, and State of New York, have invented a new, original, and ornamental Design for a Textile Fabric or Similar Article, of which the following is a specification, reference being had to the accompanying drawing, forming a part thereof.

The dot and dash lines on the drawing outline the design unit, which unit is repeated in regular succession, as indicated by the extensions beyond the unit boundaries. The drawing is lined to indicate shading.

I claim:

The ornamental design for a textile fabric or similar article as shown and described.

In testimony whereof I have signed this specification.
